(57) CLAIM

We claim the ornamental design for a tub filler, as shown and described.

DESCRIPTION

FIG. 1 is a top, front, right perspective view of a tub filler;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.
